UNITED STATES PATENT OFFICE.

JOSEPH J. PARENT, OF AUBURN, MAINE.

SWING-CANOPY.

1,104,309.

Specification of Letters Patent. Patented July 21, 1914.

Application filed May 7, 1913. Serial No. 766,199.

To all whom it may concern:

Be it known that I, JOSEPH J. PARENT, a citizen of the United States, residing at Auburn, in the county of Androscoggin and State of Maine, have invented new and useful Improvements in Swing-Canopies, of which the following is a specification.

This invention relates to canopies and more particularly to swing canopies.

10 The principal object of the invention is to provide an inexpensive structure which may be folded into compact form when not in use so as to take up little space and which may be readily attached to and detached 15 from swings of different sizes or dimensions.

Further objects of the invention will appear as the following description is read in connection with the accompanying drawing which forms part of this application, and 20 in which:—

Figure 1 is a side elevation. Fig. 2 is a top plan view with parts broken away. Fig. 3 is a vertical sectional view on the line 3—3 of Fig. 2.

25 For the purpose of illustrating the operation of my invention I have shown an ordinary swing which is constructed, as is usual, of separate pairs of uprights 1 and 2 connected together by the diagonal braces 3 and 30 4. The members of the separate pairs of uprights are connected together, as is usual, by transverse braces 5 and 6.

The canopy comprises separate frames 8 and 9 each consisting of a plurality of longitudinal members 10 connected together by cross bars 11 and 12. The cross bars 11 are secured to the ends of the longitudinal members while the cross bars 12 are secured to the sides of the longitudinal members intermediate their length. The upper ends of the longitudinal members 10 all have secured thereto hinge members 13 which are connected together by a single longitudinal hinge rod 14 which extends the full width 45 of the frames. Covering both of the frames and extending over the hinge rod is suitable covering 15 which is preferably made of some water-proof fabric, such as canvas or the like.

50 The canopy is secured to the swing frame by means of four brackets each one of which is constructed in a similar manner to that shown in Fig. 3 and each comprises separate parts 16 and 17. The part 16 consists

of a substantially V-shaped strip of metal 55 having one terminal bent back upon itself to extend beneath the cross bar 12 where it is secured to said cross bar by means of a screw bolt which passes through the bent back portion and through the main portion 60 of the member 16. The opposite end of the member 16 is bent at approximate right angles to that leg and is slotted to receive a screw which passes therethrough and enters a threaded aperture in the part 17, the 65 part 17 being substantially L-shaped so as to extend beneath the cross bar 6 of the swing whereby the canopy frames are prevented from raising or becoming disconnected from the swing. By removing the 70 hooks or L-shaped members 17 from the brackets 16 the canopy may be disconnected from the swing and folded one section upon the other so as to occupy small space when packed away. It will be noticed that by 75 hinging both the frames together the device may be adjusted to any size swing and the construction of the bracket is such that the canopy may be applied to almost any type of lawn swing.

80 What is claimed is:

1. A folding canopy for lawn swings comprising a pair of frames hingedly connected to each other, a canopy covering extending over said frames, and brackets carried by 85 said frames for fastening the same to the transverse braces of a swing, each of said brackets comprising a bracket member carried by the frame for engaging said transverse brace and means for clamping said 90 bracket member to said brace.

2. A folding canopy for lawn swings comprising a pair of frames hingedly connected to each other, a canopy covering extending over said frames, said frames each comprising side bars, an end bar and a cross bar, brackets carried by said cross bars for supporting the same from the transverse braces of a swing, and removable hook members carried by said bracket members for clamping 95 the same to said braces.

100 In testimony whereof I affix my signature in presence of two witnesses.

JOSEPH J. PARENT.

Witnesses:

ARTHUR J. PARENT,
CHARLES L. CARR.
